UNITED STATES PATENT OFFICE.

OLIVE E. FRANK, OF BUFFALO, NEW YORK, ASSIGNOR TO O. E. FRANK HEATER & ENGINEERING CO., INC., OF BUFFALO, NEW YORK, A CORPORATION OF NEW YORK.

HEAT INTERCHANGER.

Application filed December 6, 1927. Serial No. 238,102.

This invention relates to improvements in heat interchangers and more particularly to the type of construction which includes a two-part shell longitudinally delimiting a 5 heat exchange chamber, at least two sets or "nests" of tubes arranged in the chamber to provide a path for the flow of one of the fluids, and a baffle plate interposed between each set of tubes and the adjacent set to 10 prescribe the path of flow of the other fluid.

An object of the invention is to provide a form and arrangement of such elements as will insure the positive centering of the baffle plate with suitable seals along its margins and will permit the easy and quick removal of the baffle plate upon the removal of one section of the shell, thereby rendering all the tubes completely accessible for inspection, cleaning or repair.

20. With the above object in view the invention is directed to the combination of the shell parts, tube nest and baffle plate wherein in the form and arrangement of the elements is such that the baffle plate is positively held 25 and centered in position solely by the co-operation of the shell sections without the use of additional securing means, the marginal portions of the baffle plate having such engagement with the shell sections that leakage 30 of the fluid past said marginal portions is prevented, and wherein upon the removal of one section of the shell, the baffle may be freely removed by pulling it transversely, and in a direction of its plane from its position 35 between the tube nests.

Embodiments of my invention are shown in the accompanying drawings, wherein:

Figure 1 is a longitudinal section taken along the center line of the unit at right angles to the main baffle plate.

Figure 2 is a sectional view taken along line 2-2 of Figure 1.

Figure 3 is a sectional view taken along line 3-3 of Figure 1.

45. Figure 4 is a sectional view of a slightly modified construction taken along a line corresponding to line 2-2 of Figure 1.

As related before, the heat exchange chamber indicated at 1 is delimited by a split shell or casing 2 which preferably is composed of two sections bolted or otherwise removably secured together. The shell is formed with fluid inlet and outlet openings 3 and 4, preferably arranged opposite to 55 each other, adjacent to one end of the shell,

these openings being, of course, in open communication with the chamber 1. In order to provide a tortuous path for the fluid passing through the chamber, a baffle plate 5 is longitudinally interposed within 60 the chamber whereby the inlet fluid must pass along one side of the baffle to the opposite end of the shell, returning along the other side of the baffle to the outlet opening 4.

The path for the other fluid includes two tube nests 6 which pass through the chamber 1 on opposite sides of the baffle plate 5. The tubes of each nest 6 are supported at one end by a plate 7 which is interposed and 70 securely held between the adjacent end of the shell 2 and a head 8 by any suitable securing means. The tubes pass through the plate 7 and are in open communication with the interior of the head 8. The head 8 is 75 provided with inlet and outlet openings 9 and 10 and preferably is divided into three compartments A, B and C by partitions 11. The end of the head is closed by a cover 12.

The opposite ends of the tubes are embedded in and pass through individual plates 13 and 14 respectively and communicate with the interior of the floating heads 15 and 16 respectively. The provision of individual floating heads permits the expansion 80 and contraction of the tube nests independently of each other and of the shell. If desired, however, only one floating head may be utilized, such head having separate chambers for the separate tube nests. This end 85 of the shell is closed by a cover 17 secured to the shell.

The tortuous fluid path defined by the chamber 1 and baffle plate 5 is further obstructed by baffles 18 placed transversely of 90 both the chamber 1 and the tube nests 6. These baffles are staggered so that alternate baffles abut against the baffle plate 5 and the wall of chamber 1 respectively.

From the foregoing it will be apparent 100 that any fluid passing through the inlet opening 3 must travel alternately toward the baffle plate 5 and the wall of chamber 1 until it reaches the opposite end of the shell whence it passes around the end of the baffle 105 to the other side of the shell and returns in like manner to the outlet opening 4.

In connection with the path of flow just described, it is noted that a portion of each set of tubes extends between the tube sheet 110

7 and the inlet and outlet openings 3 and 4 respectively. It is evident that these portions are not in the direct path of flow and consequently in order to utilize the entire active surface of the tubes, it is necessary to provide means for directing the flow of fluid into the space occupied by these portions of the tubes. This is accomplished by providing a baffle plate adjacent each opening (inlet and outlet) as indicated at 19, which baffle plate extends longitudinally of the shell from the first of the transverse baffles 18 on the floating head side of the inlet and outlet openings, to a point short of the tube sheet 7, the longitudinal edges of the baffle plate 19 being in abutting relation with the walls of the shell. By this arrangement the inlet and outlet openings are placed in sole communication with the space adjacent the tube sheet 7 whereby any fluid flowing through these openings is compelled to pass through such space and, therefore, around the otherwise inactive surface of the tubes.

25 The other fluid passing through the inlet opening 9 and the adjacent chamber A, must travel through some tubes in one of the tube nests 6 to the chamber of head 15 from which it returns through the remaining tubes of the same nest back to chamber B. From chamber B the cycle is repeated through the other tube nest, the fluid passing through some tubes in said nest to the chamber in head 16 and returning through the remaining tubes of the same nest to the chamber C whence it passes to the outlet opening 10.

Because of the nature of the liquids and gases flowing through heat exchangers, frequent cleaning of the outside of the tubes and the interior of the heat exchange chamber is necessary for successful and economical operation. One of the features of this invention is the provision for the ready removal of the baffle plate 5 whereby both tube nests are accessible for inspection or cleaning purposes. This is accomplished by internally rabbeting one section of the shell along its longitudinal margins as at 20 to provide recesses into which the baffle plate 5 is fitted. Thus when the sections of the shell are bolted together the baffle plate will be centered accurately and held securely in place by said sections while at the same time the fluid path will be effectively sealed along the longitudinal margins of the baffle plate. In order to remove the baffle plate and thereby completely expose the tubes, it is only necessary to remove the rabbeted section of the shell, whereupon the baffle may be pulled

transversely in a direction of its plane from its position between the tube nests 6.

If desired, however, each shell may be rabbeted to form the recesses into which the baffle plate 5 is fitted, or each section of the shell may be formed with one rabbeted portion whereby when bolted together, opposed grooves result. This latter construction permits the shell sections to be interchangeable and is illustrated in Figure 4, wherein the baffle plate 5^a is fitted on one side, in the rabbeted portion of one shell section and on the other side, in the rabbeted portion of the other shell section.

While the invention has been illustrated as applied to specific embodiments of heat interchangers, it is to be understood that it is not limited thereto but may be applied to any suitable vertical or horizontal unit.

Having fully described my invention, I claim:

1. A heat interchanger comprising a shell composed of at least two sections removably secured together and delimiting a heat exchange chamber, two tube nests in said chamber providing a path for the flow of one of the fluids, the shell being formed with grooves along its longitudinal margins, and a baffle plate interposed between the tube nests prescribed a path of flow for the other fluid and having its longitudinal marginal edges arranged in said grooves whereby the path of flow of said other fluid is sealed along said marginal edges of the baffle and the baffle centered and held in position and wherein, upon the removal of at least one section of the shell, the baffle may be freely removed.

2. A heat interchanger comprising a shell composed of at least two sections removably secured together and delimiting a heat exchange chamber, two tube nests in said chamber providing a path for the flow of one of the fluids, one section of the shell being internally rabbeted along its longitudinal margins and cooperating with the other section to form opposed grooves, and a baffle plate interposed between the tube nests prescribing a path of flow for the other fluid and having its longitudinal marginal edges arranged in said grooves whereby the path of flow of said other fluid is sealed along said marginal edges of the baffle and the baffle centered and held in position and wherein, upon the removal of at least one section of the shell, the baffle may be freely removed.

In testimony whereof I hereby affix my signature.

OLIVE E. FRANK.
